UNITED STATES PATENT OFFICE.

WILLETT J. HICKMAN, OF SHREVEPORT, LOUISIANA.

PORTABLE HOIST.

Application filed December 22, 1921. Serial No. 524,198.

To all whom it may concern:

Be it known that I, WILLETT J. HICKMAN, a citizen of the United States, and a resident of Shreveport, in the parish of Caddo and State of Louisiana, have invented certain new and useful Improvements in Portable Hoists, of which the following is a specification.

This invention relates to a portable hoist 10 for bailing lines used in connection with wells.

An important object of this invention is to provide a portable hoist for bailing lines having novel means whereby the same may 15 be expeditiously set into operation so that the loss of time on the part of the drilling crew will be reduced to a minimum.

Further the invention aims to provide a portable hoist for bailing lines which may 20 be driven by the regular drilling machinery and having novel means whereby the speed of the same may be varied.

A further and equally important aim of the invention is to provide a bailing hoist 25 which dispenses with the necessity for reeling the drilling line from draw works and rereeling the same line or bailing line each time the well is bailed, thus saving time for the drilling crew and excessive wear on the 30 line both in reeling and in moving.

By the use of this invention the drilling operation is greatly expedited and the cost of the same is materially reduced.

Other objects and advantages of the invention will be apparent during the course 35 of the following description.

In the accompanying drawing forming a part of this application and in which like numerals are employed to designate like 40 parts throughout the same,

Figure 1 is a side elevation of the same, a line or cable being shown partly wound about the drum.

Figure 2 is an end elevation of the improved hoisting apparatus.

Figure 3 is a detail view illustrating the breaking means.

Figure 4 is a vertical transverse sectional view taken on line 4-4 of Figure 2.

In the drawing wherein for the purpose 50 of illustration is shown a preferred embodiment of the invention the numerals 5 designate a pair of spaced parallel skids upon which the apparatus is mounted, said skids 55 forming a means whereby the apparatus may be conveniently transported when de-

sired and whereby the apparatus may be conveniently placed in position.

As illustrated particularly in Figure 1 a pair of standards 6 extend upwardly from the skids 5 and are provided with cap bearings 8 which support a shaft 9. A drum generally designated by the numeral 10 is secured upon the shaft 9 and is provided with a hub 11 and end flanges 12 and 13, 65 the said flanges forming a means to hold the cable 14 in position on the drum.

When the cable is connected to the drum it is also trained about a spooling sheave 18 70 rotatably mounted upon a spooling shaft 20 connected at its ends to the standards 6.

As illustrated in Figures 1 and 3 the flange 13 is provided with a drum 22 about which a brake band 24 is extended. The brake band which is provided with a lining 75 26 has one end connected to the spooling shaft 20 by means of an attaching strap 28 and by means of a pair of spaced ears 30. The spaced ears 30 are connected to the attaching strap 28 by means of a pin 32. The 80 ears 30 which are of elongated formation are rigidly secured upon the shaft 20 but when the shaft is manually rotated by a means to be later described the outer terminal portions of the ears will be moved 85 either downwardly or upwardly for operating the brake band. It will be seen that when the outer portions of the ears 30 are moved downwardly the brake band 24 will be tightened about the drum 22 and when 90 the ears are moved upwardly or in a clockwise direction the brake band will be loosened. The brake band forms a means whereby the speed of the drum may be varied.

95 A brake lever 29 is provided with an attaching portion 35 secured upon the spooling shaft 20. It will be seen that when the lever 29 is operated the shaft 20 will be moved in a clockwise or anti-clockwise direction for controlling the brake band.

The shaft 9 has a sprocket wheel 36 mounted thereon and engaged by a sprocket chain connected to a suitable source of power. The sprocket wheel 36 is provided 105 with a hub 38 having oppositely arranged sockets 39 receiving the extensions 40 on a clutch section 41 splined upon the main shaft 9.

When the clutch section 41 is moved 110 longitudinally into engagement with the hub 38 the driving connection is provided

between the sprocket wheel 36 and the main shaft whereby the drum is rotated.

The clutch section 41 may be moved longitudinally of the main shaft by means of an 5 operating lever 44 having its forward portion provided with a yoke 46 extending on opposite sides of the clutch section. Suitable means are employed for connecting the upper and lower sides of the yoke 46 to the 10 clutch section so that the same is constrained to operate with the lever. With reference to Figure 2 it will be observed that the forward portion of the lever 44 is pivotally supported by means of a bracket 15 47 secured as indicated at 48 to the adjacent standard 6.

In operation, when it is desired to wind the cable upon the drum it is merely necessary to establish a driving connection between the drum and the main shaft 9 by 20 means of the aforesaid clutch section and when the power unit is set into operation, the drum will be rapidly rotated for winding the cable thereon.

25 The improved line hoisting apparatus may be conveniently mounted upon the platform of a well and secured thereon by bolts or other suitable fastening devices.

With reference to the foregoing description taken in connection with the accompanying drawings it will be apparent that 30 a hoisting apparatus constructed in accordance with this invention may be expedi-

tiously operated for reducing the loss of time to a minimum when drilling a well.

As illustrated particularly in Figures 1 and 3 a pair of eye-bolts 50 are mounted upon the spooling shaft on opposite sides of the attaching strap 28 and are provided with threaded shanks 51 adjustably connected to one end of the brake band so that the tension of the band may be varied at will.

Having thus described the invention what is claimed is:—

An apparatus of the class described comprising a base, standards mounted thereon, a shaft supported by said standards, a drum mounted on said shaft and having a brake drum, a spooling shaft supported by said standards and having a spool rotatable thereon, a brake band trained about said drum, an ear connected to one end of said brake band and being rigidly secured to said spooling shaft, an eye bolt connected to the other end of said brake band and rotatable on said spooling shaft, a lever rigidly connected to said spooling shaft for rotating the same, a power transmitting member mounted on said first-named shaft, and clutch means whereby a driving connection between the power transmitting member and the first-named shaft may be established.

WILLETT J. HICKMAN.
